UNITED STATES PATENT OFFICE.

ROBERT S. DRUMMOND, OF DETROIT, MICHIGAN, ASSIGNOR TO DETROIT STEEL PRODUCTS COMPANY, OF DETROIT, MICHIGAN, A CORPORATION OF MICHIGAN.

METALLIC WINDOW-SASH.

1,158,461.

Specification of Letters Patent. Patented Nov. 2, 1915.

Application filed April 24, 1913. Serial No. 763,353.

To all whom it may concern:

Be it known that I, ROBERT S. DRUMMOND, a citizen of the United States of America, residing at Detroit, in the county of Wayne 5 and State of Michigan, have invented certain new and useful Improvements in Metallic Window-Sashes, of which the following is a specification, reference being had therein to the accompanying drawings.

10 The invention relates to metallic window sashes and has more particular reference to certain features of construction by which adjacent sash sections may be secured to each other so as to provide for expansion 15 and contraction, and also to form a weathering joint.

In the drawings: Figure 1 is a front elevation of a sash formed of a plurality of sections. Fig. 2 is an enlarged horizontal 20 section showing the joint between sections. Fig. 3 is a similar view showing a modified construction; and Figs. 4 and 5 are similar views showing other modifications.

My improved sash comprises essentially a 25 plurality of sections which are spaced from each other to provide for expansion, one of said sections being also provided with a flange which overlaps the adjacent section and forms a weathering joint. The sections 30 are secured to each other by suitable means, which will permit of expansion and contraction, and at the same time will hold said sections always in true alinement.

As shown in Figs. 1 and 2, A A' and A² 35 are the several sections of the sash, the adjacent rails of which are spaced from each other. One of the adjacent rails is formed of a Z-bar B, having an outwardly-extending flange C which overlaps the rail of the 40 adjacent sash and covers the space therebetween so as to weather the joint.

The adjacent rails are mechanically secured to each other by bolts D which pass through the parallel webs or flanges of adjacent rails and hold the sections in alinement while permitting them to move toward or from each other in expanding and contracting.

In Fig. 3, a modified form of securing 50 means is shown, in which the adjacent rails E and F are held in alinement by a plate G which is secured by bolts H to the alined flanges of said rail. These bolts pass through slotted bolt holes I in the plate

which provide for expansion and contraction. 55

In Fig. 4 another modification is shown in which, in place of a Z-bar, angle bars and K form the adjacent rails, while one of said bars has secured thereto another angle bar L, which forms in effect a Z-bar and overlaps the adjacent rail in a similar manner to the construction shown in Fig. 2. These sash sections may be secured together by either or both of the securing means as shown in Figs. 2 and 3; a bolt M being shown as passing through the parallelly-arranged spaced flanges of the rails, while a plate N is secured by bolts O to alined faces of said rails. 71

In Fig. 5, the sash sections are also formed of angle bars P and Q, which are spaced from each other, while a T-bar R is arranged with its web extending into the space between said bars P and Q, the head 75 of the T overlapping the edges of said bars. A bolt S passes through the parallel flanges of the sash rails and also the web of the T and secures the parts to each other, while permitting of expansion. 80

With all of the constructions as above described, the sash sections are held in true alinement and are permitted to freely expand and contract, while the joint is thoroughly weathered. 85

What I claim as my invention is:

1. In an expansion joint for metallic windows, sash sections provided with edge rails, one of said sections having its edge rail spaced from an adjacent section, a flange on 90 said first-mentioned section extending outward and overlapping the adjacent section, and a bolt for securing said sections to each other permitting of independent movement.

2. An expansion joint for metallic windows, comprising a plurality of sections having parallelly-arranged spaced edge bars, a flange on one bar overlapping the edge of the adjacent bar and weathering the joint therebetween, and a bolt connecting the parallel portions of said sections to hold the same in alinement and permitting of expansion and contraction. 95

3. In an expansion joint for metallic windows, sash sections provided with edge rails, one of said sash sections having its edge rail spaced from an adjacent edge rail of a second section, a flange on said first-mentioned 100

105

- section extending outward and overlapping the adjacent edge rail, and adjustable means for securing said edge rails to each other, permitting of independent movement.
- 5 4. An expansion joint in a metallic window, comprising a plurality of adjacent sections having sash rails with spaced parallelly-arranged flanges, a member on one of said sash rails overlapping the edges of said 10 spaced flanges, and a bolt connecting said

spaced flanges to hold the same in alinement and permitting of expansion and contraction, said bolt securing said overlapping member in position upon its sash rail.

In testimony whereof I affix my signature 15
in presence of two witnesses.

ROBERT S. DRUMMOND.
